UNITED STATES PATENT OFFICE.

JOSEPH DAIN, OF MOLINE, ILLINOIS, ASSIGNOR TO DAIN MANUFACTURING COMPANY
OF IOWA, OF OTTUMWA, IOWA, A CORPORATION OF IOWA.

HAY-PRESS.

1,153,199.

Specification of Letters Patent. Patented Sept. 14, 1915.

Application filed December 22, 1913. Serial No. 808,194.

To all whom it may concern:

Be it known that I, JOSEPH DAIN, a citizen of the United States, residing at Moline, in the county of Rock Island and State 5 of Illinois, have invented certain new and useful Improvements in Hay-Presses, of which the following is a specification, reference being had to the accompanying drawings.

10 My invention relates to hay presses, and particularly to presses of the type shown and described in my pending application, Serial No. 721,354, filed September 20, 1912, in which the plunger by which the hay is compressed is operated by an eccentrically-mounted gear, or gears, rotated by means of pinions carried by a drive-shaft, which in turn is driven from a suitable source of power, such as a gasoline engine, mounted 15 on the carriage of the press. In such presses, owing to the eccentric mounting of the drive gears, it is necessary that the pinions which drive said gears move toward and from the axis of rotation of said eccentric gears so that they may constantly 20 mesh therewith, and one of the objects of my present invention is to provide improved means for mounting such pinion or pinions so that they may constantly be held in 25 proper relation to the eccentric gear or gears. In such presses, it is also desirable to vary the tension of the belt or belts by which the drive-shaft is driven from the engine, so as to increase the belt tension during 30 the compression stroke, at which time the greatest power must be applied to the eccentric gears, and to reduce such tension during those parts of the stroke when less power is required, and another object of 35 my present invention is to provide for automatically securing this variation in the tension of the belt.

A further object is to provide for accommodating the tension-regulating devices to 40 engines of different makes and sizes.

I accomplish these objects as illustrated in the accompanying drawings and as herein-after described.

What I regard as new is set forth in the 45 claims.

In the accompanying drawings, Figure 1 is a side elevation of my improved press; Fig. 2 is a plan view thereof; Fig. 3 is an enlarged detail, being a partial side elevation 50 of the eccentric gears and some of the

associated parts; and Fig. 4 is a plan view of the parts shown in Fig. 3.

Referring to the drawings, 5 indicates the frame of the press, which may be of the usual construction, and in the illustration 60 is shown as mounted on wheels 6, so that it may be transported. 7 indicates the baling chamber, and 8 the plunger, which is preferably a rocking plunger, of the type shown in my application hereinbefore referred to. 9 indicates eccentrically-mounted driving gears which are arranged parallel to each other a short distance apart, as shown in Fig. 2, and are mounted on pinions 10 eccentrically disposed, as shown in Fig. 70 1, the gears themselves being circular. 11 indicates the bearings in which the pinions 10 are fitted. The plunger 8 is connected with the gears 9 by a wrist pin 12, as shown in Fig. 1, the arrangement being such that as the gears 9 rotate, the plunger 8 is moved back and forth. These parts are all substantially the same as the corresponding parts shown and described in my said pending 75 application.

13 indicates a gasoline or other suitable engine which is mounted on the frame 5 on a support 14 movable longitudinally of said frame by means of a crank 15. 16 indicates the crank-shaft of the engine, and 17 pulleys mounted thereon. 18 indicates fly wheels, also mounted on the crank-shaft 16. These parts also are substantially the same as those shown and described in my said application. 80

19 indicates a drive shaft, which, as shown in Figs. 3 and 4, is mounted in suitable bearings provided in arms 20, pivotally connected with the gears 9 at the center thereof, as shown at 21 in Fig. 3. The arms 20, therefore, extend radially from the centers of the gears 9, and slightly beyond the peripheries thereof, the arrangement being such that they operate to hold the shaft 19 at such a distance from the peripheries of the gears 9 that pinions 22 carried by said shaft always mesh properly with the gears 9, as shown in Fig. 4. 95

23 indicates links, which at one end are connected with a sleeve 24, mounted on the shaft 19, adjacent to the pinions 22, and at the other end are adjustably connected with standards 25 rising from the frame 5, as shown in Fig. 1. The links 23 coöperate with the arms 20 to hold the shaft 19 in proper operative relation to the gears 9, and 100 105 110

as shown in Figs. 1 and 3, they are so arranged as to hold said shaft in a position above said gears and between the pulleys 17 and a vertical plane passing through the 5 axes of said gears 9. It will be seen, therefore, that as the gears 9 rotate, the shaft 19 will rise and fall, as determined by the eccentricity of said gears, but the pinions 22 will always remain in mesh with said gears, 10 the eccentricity of the latter being automatically compensated for.

26 indicates pulleys carried by the drive shaft 19, and 27 indicates belts connecting said pulleys with the pulleys 17 on the 15 crank-shaft 16. As clearly shown in Fig. 3, the links 23 are connected with the standards 25 at a point lying slightly above a line connecting the crank-shaft 16 with the drive-shaft 19 when the latter is at its highest 20 point. The result is that as the drive-shaft 17 falls, owing to its moving closer to the axis of rotation of the gears 9, said shaft 19 and the pulleys carried by it will be moved closer to the crank-shaft 16, owing 25 to the change in the angular position of the links 23, thus reducing the tension on the belts 27. On the other hand when the drive-shaft 17 is moved upwardly, the nearer the 30 links 23 approach to coincidence with a line connecting the shaft 19 with the crank-shaft 16, the greater will be the tension upon the belts 27. As the latter movement takes place when the shaft 19 is at its greatest distance from the axis of rotation of the gears 9, 35 which is during the compression stroke, it will be apparent that during the compression stroke the tension upon the belts 27 will be the greatest, and that after the completion of the compression stroke, at which time 40 the drive shaft 19 approaches closer to the axis of rotation of the gears 9, the tension upon the belts 27 will be reduced.

In order that the tension-governing devices may be adjusted, the links 23 are connected with the standards 25 so that the ends shown at the left-hand in the illustration may be moved up or down, this being preferably accomplished by providing a series of 45 holes 28 in the standards 25 to receive the 50 bent ends of said links, as shown in Figs. 3 and 4. Obviously, if the ends of the links 23 be placed in the topmost holes 28, the other connections remaining the same, the greatest tension upon the belts 27 will be less 55 than where the links are placed in the intermediate holes, or in the lowermost holes. This construction also provides for adapting the apparatus to engines of different sizes or makes, since the distance from the base 60 of the engine to the crank-shaft varies with different engines. The standards 25 are preferably mounted as close to the engine fly wheel as possible, so as to give a reasonable length to the links 23, and thereby avoid 65 extreme variation of the belt tension.

It will be understood that the drawings illustrate one embodiment of my invention, and that it may also be embodied in various other forms. The claims hereinafter made are therefore to be construed accordingly.

What I claim as my invention, and desire to secure by Letters Patent, is,—

1. A press, comprising an eccentrically-mounted gear, a plunger operated thereby, a rising and falling pinion meshing with said gear, means supporting said pinion and holding it constantly in mesh with said gear, and means for driving said pinion.

2. A press, comprising an eccentrically-mounted gear, a plunger operated thereby, a vertically-movable pinion meshing with said gear, means supporting said pinion and holding it constantly in mesh with said gear, and means for driving said pinion.

3. A press, comprising an eccentrically-mounted gear, a plunger operated thereby, a pinion meshing with said gear, means centrally connected with said gear and with said pinion, for holding the same in mesh with said gear as the latter rotates, a swinging support for said pinion, and means for driving said pinion.

4. A press, comprising an eccentrically-mounted gear, a plunger operated thereby, a pinion meshing with said gear, means centrally connected with said gear and supporting said pinion for holding the same in mesh with said gear as the latter rotates, a link pivotally mounted upon the machine frame and co-operating with said supporting means for positioning said pinion with reference to the gear, and means for driving said pinion.

5. A press, comprising an eccentrically-mounted gear, a plunger operated thereby, a circular pinion meshing with said gear, means for holding said pinion in mesh with said gear during the rotation of the latter, and means for driving said pinion.

6. A press, comprising an eccentrically-mounted gear, a plunger operated thereby, members disposed angularly with relation to each other, a shaft supported by said members at the juncture thereof, a pinion carried by said shaft and meshing with said gear, and means for driving said shaft.

7. A press, comprising an eccentrically-mounted gear, a plunger operated thereby, a drive-shaft, a pulley carried thereby, a drive pulley, a belt connecting said pulleys, a pinion carried by said shaft and meshing with said gear, and means for moving said shaft toward and from said drive pulley during different stages of the rotation of said gear, to vary the tension of said belt.

8. A press, comprising an eccentrically-mounted gear, a plunger operated thereby, a drive-shaft, a pinion carried by said shaft and meshing with said gear, a pulley mounted on said shaft, a drive pulley, a belt con-

necting said pulleys, and a swinging link connected with said drive-shaft and with a suitable support, said link being adapted when swung to vary its angular relation to a line connecting said shaft with the axis of said drive pulley, whereby the tension of the belt will vary with the swinging of said link.

5 9. A press, comprising an eccentrically-mounted gear, a plunger operated thereby, a drive-shaft, a pinion carried by said shaft and meshing with said gear, a pulley mounted on said shaft, a drive pulley, a belt con-

necting said pulleys, and a swinging link connected with said drive-shaft and adjustably connected with a suitable support, said link being adapted when swung to vary its angular relation to a line connecting said shaft with the axis of said drive pulley, whereby the tension of the belt will vary with the swinging of said link.

15 JOSEPH DAIN.
